VEHICLE FOR VENDING ICE CREAM OR THE LIKE

Albert J. Miller, Jr., 859 Savaker Ave., San Jose, Calif.

Filed Apr. 4, 1962, Ser. No. 69,586

Term of patent 14 years

(Cl. D14—3)

The dominant portions of my design reside in the solid line portions of the drawing.

I claim:

The ornamental design for a vehicle for vending ice cream or the like, substantially as shown and described.
